UNITED STATES PATENT OFFICE.

GEORGE SIMEONOFF, OF COVINA, CALIFORNIA.

COLLAPSIBLE SEWING BASKET.

Application filed January 17, 1925. Serial No. 3,050.

My invention relates to baskets more particularly to a collapsible sewing basket and the objects of my invention are:

First, to provide a sewing basket which is collapsible and may be positioned flat for shipping purposes.

Second, to provide a sewing basket which is flexible and supported at the top by means of a cord so that the size of the basket at the top may be varied as desired.

Third, to provide a sewing basket of this class with variously shaped pockets for sewing material, buttons, scissors and the like, all secured to the interior of the outer side sections of the basket.

Fourth, to provide a novelly constructed basket to be used for sewing purposes and—

Fifth, to provide a basket of this class which is very simple and economical to make, durable, efficient, practical and which will not readily deteriorate or get out of order.

With these and other objects in view as will appear hereinafter, my invention consists of certain novel features of construction, combination and arrangement of parts and portions as will be hereinafter described in detail and particularly set forth in the appended claims, reference being had to the accompanying drawings and to the characters of reference thereon which form a part of this application, in which:

Figure 1, is a top or plan view of my basket shown in its collapsed or flat form showing certain portions broken away to facilitate the illustration. Fig. 2 is a side elevational view of the same when folded into basket form ready for use as a basket. Fig. 3 is a sectional view on an enlarged scale through 3—3 of Fig. 1. Fig. 4 is a detailed side elevational view of one of the reinforcing members for reinforcing the side sections, and Fig. 5 is a similar view to that of Fig. 1 showing a fragmentary portion of the basket in a slightly modified form from that of the other views of the drawings.

Similar characters of reference refer to similar parts and portions throughout the several views of the drawings.

The inner fabric 1, outer fabric 2, pockets 3, 4 and 5, reinforcing members 6, button pocket 7, scissors pocket 8, pin cushion 9, central and bottom portion 10, takeup cord 11, and eyelets 12, constitute the principal parts and portions of my sewing basket.

My basket in the preferred form consists

of a circular piece of fabric 1, another circular piece of fabric of the same size 2, placed one upon the other and positioned between these two fabric members 1 and 2 60 in the center is a reinforcing member 10^a, preferably cardboard which is hexagon shaped, positioned on the six sides of said hexagon shaped member 10^a are six members 6 as shown best in Fig. 4 of the drawings which are reinforcing members, preferably cardboard and positioned between said fabric members around the outer edge, then the two members 1 and 2 are sewed together, along the outer edge of member 10 and 70 around each of the members 6 as shown best in Fig. 1 of the drawings. The outer edge is then provided with a binding 1^a. Thus in the flat position is shown a circular member with cardboard reinforcing. Positioned on 75 three of these sections are pockets, 3, 4 and 5 which are also preferably of fabric in ruffled form and each provided with an elastic band, 3^a, 4^a and 5^a, tending to hold the pockets closed at their open sides and each is 80 provided centrally with a bow 3^b, 4^b and 5^b, which is adapted for a hold member to facilitate the opening of the outer side. On one of the sections is mounted a pin cushion 9, which is secured thereto. One of the sections is provided with a plurality of ribbons 8^a, spaced apart from each other and secured at the middle at 8^b, thus forming pockets for 85 scissors or the like and the section 7 is provided with another cardboard member 6, 90 covered with fabric on both sides 7^a and 7^b and with binding around the same and with fabric at each side connecting with the inner portion 1 and folding toward the middle, forming a tight pocket for buttons, each of 95 the members 7 and the section upon which it is mounted is provided with a ribbon 7^c and 7^d which are adapted to be tied together forming a closure for the button pocket member. Secured near the edge of each of 100 the pockets is an eye member 12, through which the cord 11 extends, thus providing a takeup cord for drawing the upper portion of the basket together to the position desired as shown best in Fig. 2 of the 105 drawings, the space between the outer sections extending outwardly in loop form, the ends of the cord are tied together, thus forming a substantial basket for sewing purposes, which may be opened out flat to 110 get at the contents of the basket better or for shipping purposes.

In the modified form of construction shown in Fig. 5 of the drawings the fabric between the various outer sections is cut away leaving an open space and each of the sections is provided with binding around its outer edge, the construction, otherwise, being the same as that shown and described in Figures 1 to 4 inclusive.

Though I have shown and described a particular construction, combination and arrangement of parts and portions and a certain modification thereof, I do not wish to be limited to this particular construction, combination and arrangement nor to the modification but desire to include in the scope of my invention, the construction, combination, and arrangement substantially as set forth in the appended claims:

Having thus described my invention what I claim as new and desire to secure by Letters Patent is:

1. In a collapsible basket, a polygon shaped central member, a plurality of stiff sections flexibly connected to the outer sides of said polygon shaped member, eye members secured near the outer edges of said section and extending inwardly therefrom and a cord through said eye members, adapted to pull said sections toward each other forming a basket structure, a plurality of pockets in connection with the inner sides of some of said outer sections with elastic gathering members near the open sides of said pockets tending to hold the pockets closed, and a reinforced member hingedly connected to one of said outer sections near its inner edge, provided with flexible side members forming a pocket between said hinged member and the main section mem-

ber and ribbons connecting the outer edges 40 together.

2. In a collapsible sewing basket, an outer fabric member, an inner fabric member, a central reinforcing member positioned between said fabric member and the fabric members sewed together around said central reinforcing member, a plurality of outer reinforcing members positioned between said fabric members at their outer sides and sewed around their outer edges, and the fabric members sewed together at their outer edges, a plurality of eye members secured to the inner surface of the inner main fabric member near the outer edge and cord run through said eye members adapted to draw the outer sections together forming a basket.

3. In a collapsible sewing basket, an outer fabric member, an inner fabric member, a central reinforcing member positioned between said fabric members and the fabric members sewed together around said central reinforcing member, a plurality of outer reinforcing members positioned between said fabric members at their outer sides and sewed around their outer edges, and the fabric members sewed together at their outer edges, a plurality of eye members secured to the inner surface of the inner main fabric member near the outer edge, cord run through said eye members adapted to draw the outer sections together forming a basket, and variously formed pockets secured on the inner surfaces of the outer sections.

In testimony whereof, I have hereunto set 75 my hand at Covina, California, this 30th day of December, 1924.

GEORGE SIMEONOFF.
